No. 37,303.

Patented January 24, 1905.

UNITED STATES PATENT OFFICE.

GEORGE DAYTON KINSEY, OF BROOKLYN, NEW YORK, ASSIGNOR TO THE UNITED STATES PRINTING COMPANY, OF CINCINNATI, OHIO, A CORPORATION OF OHIO.

DESIGN FOR A LABEL.

SPECIFICATION forming part of Design No. 37,303, dated January 24, 1905.

Application filed December 15, 1904. Serial No. 237,037. Term of patent 14 years.

To all whom it may concern:

Be it known that I, GEORGE DAYTON KINSEY, a citizen of the United States, residing at Brooklyn, county of Kings, and State of New York, have invented a new, original, and ornamental Design for Labels, of which the following is a specification, reference being had to the accompanying drawing, forming a part thereof.

10 The figure is a plan view of a label, showing my new design.

What I claim as new, and desire to secure by Letters Patent, is—

The ornamental design for a label, substantially as herein shown.

GEO. DAYTON KINSEY.
